J. J. GETGEY,
DEVICE FOR HANGING AND PRESSING TROUSERS.
APPLICATION FILED NOV. 3, 1919.

1,400,741.

Patented Dec. 20, 1921.

UNITED STATES PATENT OFFICE.

JOHN J. GETGEY, OF TULSA, OKLAHOMA.

DEVICE FOR HANGING AND PRESSING TROUSERS.

1,460,741.

Specification of Letters Patent. Patented Dec. 20, 1921.

Application filed November 3, 1919. Serial No. 335,265.

To all whom it may concern:

Be it known that I, JOHN J. GETGEY, a citizen of the United States, residing at Tulsa, in the county of Tulsa and State of Oklahoma, have invented a new and useful Device for Hanging and Pressing Trousers.

This invention relates to garment hangers and pressers and has especial relation to devices for pressing and hanging trousers.

10 An object of the invention is the provision of a device of simple construction and operation, by means of which one or more pairs of trousers may be hung and held in position to retain their proper shape and smoothness.

Another object is the provision of a device of the above character, which in addition to creasing the trousers and holding them in proper longitudinal stretched position, will 20 also stretch them transversely, so that all undesirable wrinkles and creases will be eliminated.

A further object is the provision of means for separately pressing the cuffs of the trousers, separate adjustment being provided to allow for their increased thickness.

Other objects and advantages of the invention will appear as the following description is read in connection with the accompanying drawings.

In the drawings:—

Figure 1 is a side elevation of the invention.

Fig. 2 is an enlarged fragmentary edge view of the same, a portion of the device being shown in section.

Fig. 3 is an enlarged fragmentary elevation of a portion of the upper end of the invention.

Fig. 4 is a section on the line 4—4 of Fig. 1.

Referring specifically to the drawings, wherein like characters of reference denote corresponding parts, the invention is shown as comprising spaced pairs of longitudinally extending clamping members A and A', which are adapted to engage the opposite sides of a pair of trousers along the edges of the same. These members A and A' are provided at one end with hook shaped extremities C and C', the latter extending laterally from the members A and A' and passing through elongated openings B and B' provided in hanger elements X. The ele-

ments X are spaced farther apart than the members A and A' so as to provide for the increased thickness of the trousers' cuffs. The extremities of the hooks C and C' are spaced from the members A and A' to provide for the removable elements X, so that the latter may be detached when the device is packed for shipment. Connected to each of the elements X, are the opposite ends of a corrugated strap S, the latter being of substantially inverted V shape, while a ring R engages over the clamp S for the purpose of holding the elements X against outward movement after the latter have been clamped upon the trousers' cuffs. The hook H is carried for the clamp S, by means of which the device may be suspended.

The clamping members A and A' are adjustably clamped along the edges of the trousers by means of substantially U shaped clamps E, an adjusting screw K serving to hold the clamping members in position.

Pivotedly secured to one of each pair of clamping members as shown at P, is a rod G, the opposite end of these rods being provided with wedge shaped projections W, which are adapted to engage teeth T formed in the opposite clamping member of each pair. By this means the members of each pair may be relatively adjusted, the formation of the openings B and B' providing a sliding connection between the said members and the elements X.

The invention is susceptible of various changes in its form, proportions and minor details of construction and the right is herein reserved to make such changes as properly fall within the scope of the appended claims.

Having described the invention what is claimed is:—

1. A garment hanger comprising oppositely located main clamping members, means for securing the clamping members to a garment, auxiliary clamping members adjustable upon and secured to each of the main clamping members and means whereby the auxiliary clamping members may be secured to the garment.

2. A trousers hanger comprising oppositely located main clamping members, means for securing the clamping members upon the legs of the trousers, slotted auxiliary clamping members, means carried by each the main clamping members for engagement in

the slots of the auxiliary clamping members and means whereby the auxiliary clamping members may be secured upon the bottoms of the trousers independent of the main clamping members.

3. A trousers hanger comprising oppositely located main clamping members, means for securing the clamping members upon the legs of the trousers, auxiliary clamping members slidably secured to the main clamping members and capable of relative lateral adjustment and means for se-

curing the auxiliary clamping members in position.

4. A trousers hanger comprising oppositely located main clamping members, means for securing the clamping members upon the legs of the trousers, auxiliary clamping members, means extending laterally from the main clamping members for sliding engagement with the auxiliary clamping members and means for holding the auxiliary clamping members in clamped position.

JOHN J. GETGEY.
